UNITED STATES PATENT OFFICE.

JOSEPH S. COATES, OF GOSHEN, NEW YORK.

HORSESHOE CALK.

Application filed February 7, 1925. Serial No. 7,499.

The improvements relate to the class of devices commonly called horseshoe calks, and have for their objects, among others, the provision of a spring heel device employing 5 a piece of resilient material for a cushion which may be quickly and easily removed when worn and replaced by a person of ordinary skill and without the employment of tools, and which when in place will serve its 10 purpose efficiently and be automatically held in such place in spite of all the shocks and strains to which it is subjected. This provision also permits the driver to use cushions of different sizes and thereby adjust the shoe 15 to the peculiarities of different horses or to different conditions. It also makes it possible to substitute metallic or other non-resilient heel calks for the cushions when icy pavements or other conditions make it advisable.

20 The improvements are illustrated in the accompanying drawings, in which Fig. 1 is a bottom view of a horseshoe provided with heel cushions embodying the improvements;

Fig. 2 is a vertical section of the heel portion and cushion shown in Fig. 1 taken substantially on the line 2—2 thereof looking in the direction indicated by the arrows in that figure;

Fig. 3 is a top view of the heel portion of 30 the shoe shown in Fig. 1;

Fig. 4 is a bottom view of a heel portion of a shoe similar to that shown in Fig. 1 but showing a modification; and

Fig. 5 is a vertical medial section of one 35 of the removable cushions of compressible material used in embodying the improvements.

The shoe is of the usual form, and may or may not be provided with a toe calk.

40 In the preferred form the shoe 1 itself at the heel portion and on the inside is provided with an open-ended slot 2 extending from the inner edge to a point near the middle thereof at an angle other than a right angle to the longitudinal axis of the shoe, which is adapted to receive the connecting portion 3^a of the resilient cushion 3, which is so formed as to fit snugly within the said slot and fill the same, while the extending 45 portions overlap and are held in contact with the upper and lower surfaces of the shoe heel. This cushion member may be of any suitable shape and thickness, and cushions of different shapes and thickness may

be employed for different horses or to meet 55 different conditions.

In order to provide means for clamping the upper overlapping portion of the cushion on the shoe, and to give a certain amount of strength and resiliency to the 60 cushion, a tongue 4 is riveted or otherwise secured near the heel, and extends over the upper surface of the cushion so as to compress it between the said tongue and the shoe heel by the weight of the horse when the 65 shoe is in contact with the ground. In order to accommodate this tongue the shoe is provided with a step 5 to receive its forward portion, and another step 6 is provided to afford a space for the upper overlapping 70 portion of the cushion. In this manner the cushion is securely held in place and a smooth surface presented to the bottom of the horse's hoof.

The engagement of the connecting portion 3^a with the walls of the slot 2 and of the overlapping adjacent surfaces of the cushion with the heel are sufficient to hold the cushion in place under ordinary strains, but with the tongue 4 the upper section of 80 the cushion is securely clamped, and in such a manner that the greater the weight or shock the greater the clamping action. The position, form and direction of the slot 2 are also important, and it has been found by 85 careful observation and experiment that when the slot is located on the inside of the heel and extends in the general direction of the extreme end of the heel at an angle to the longitudinal axis of the shoe, the impact 90 of the shoe on the horse's hoof with the ground will have a tendency to force it toward the end of the slot, since the heel of the horse first comes in contact with the ground, and when the horse's hoof leaves 95 the ground the weight of the animal is principally on the toe, due to the lengthwise turning movement from heel to toe made by the horse in taking a step. The size, location and relative position of the slot and the 100 cushion member may, however, be varied within certain limits.

In the modified form illustrated in Fig. 4, the shoe itself is made without bends or steps, and the tongue 7 is secured to the bottom thereof and has a step or bend to space it from the bottom of the shoe, while the cushion engages a slot 8 in the tongue and

is clamped between the tongue and the bottom of the shoe. The shoe and tongue may be connected in any suitable manner, or may be made integral in either form.

5. What I claim is:

1. A horseshoe provided with an open-ended slot extending from the inner edge thereof at an inside heel portion into the interior of the shoe and rearwardly, a cushion member forming a calk having a connecting portion engaged by the edges of the slot and fitting the said slot and having portions on both sides of said connecting portion extending over the said heel portion and in permanent contact with both sides thereof.

15. 2. In combination with the device speci-

fied in claim 1, a metallic tongue secured to the shoe and extending over the heel portion thereof and over one surface of the cushion member, so as to clamp a portion of the said cushion member between the tongue and the shoe and compress the same by the weight of the animal when the shoe is on the ground.

3. In the construction specified in claim 1, the said slot being disposed at an angle other than a right angle to the longitudinal axis of the shoe.

Witness my hand this 4th day of February 1925, at the village of Goshen, county of Orange, State of New York.

JOSEPH S. COATES.
